UNITED STATES PATENT OFFICE

JOSHUA CLAYTON ROBINSON, OF HAMILTON, NEVADA.

IMPROVEMENT IN TRAMWAY-SADDLES.

Specification forming part of Letters Patent No. 121,297, dated November 28, 1871.

To all whom it may concern:

Be it known that I, JOSHUA CLAYTON ROBINSON, of Hamilton, White Pine county and State of Nevada, have invented certain Improvements in a Tramway-Saddle, of which the following is a specification:

My invention consists in combining hinged levers with jaws attached to them, and with pulleys working on the levers, for the purpose of a saddle to work on a tramway, so that when a weight is put on it holds the saddle tightly clasped on the cable, and when the weight is taken off, by means of pulleys working on the levers, the saddle is opened and freed from the cable.

Figure 1 is an end elevation of the saddle when suspended upon the cable. Fig. 2 is an end elevation when freed from the cable by the weight resting on the pulleys. Fig. 3 is an elevation of a side view of Fig. 1.

A, Figs. 1 and 2, is the frame of the saddle. B, Figs. 1 and 2, is the lower part of the frame that is turned up so as to form a hook, to which the load is attached. C, Fig. 1, is a section of the cable. D D, Figs. 1 and 2, are levers, which are hinged together. E, Figs. 1 and 2, is the hinge. F F, Fig. 1, are the jaws of the saddle clasping the cable. G G, Figs. 1 and 2, are pulleys working on the levers D D, by which the weight is taken off of the cable by the pulleys running upon a track, which is placed wherever it is desirable to free the saddle from the cable. F F, Fig. 2, shows the jaws of the saddle relieved from

the cable. G G, Fig. 2, shows the pulleys in the position that they are when resting on the track and taking the weight from the cable. A, Fig. 3, shows the frame. C C, Fig. 3, is the cable, a section of which is shown, C, Fig. 1. G, Fig. 3, is the side of the pulley G, Fig. 1. F F, Fig. 3, is the side of the jaws F, Fig. 1. H, Fig. 3, shows a slot, in which the end of the lever works upward and downward when the jaws of the saddle are opened or closed.

Now, it will be seen, by suspending the saddle upon the cable, as shown in Fig. 1, the greater the weight hung on the hook at B the tighter the jaws clasp the cable. It will also be seen that, when the weight is taken off from the cable and resting on the pulleys, the jaws are opened, as shown in Fig. 2, and freed from the cable; and, when leaving the track, the weight comes on the cable, the jaws are closed, as shown in Fig. 1.

The jaws may be lined with metal, leather, rubber, or wood, as may answer the best purpose.

I claim as my invention—

The combination of the hinged levers D D with the jaws F F and pulleys G G; also, the head of the frame A from the dotted line upward, substantially as and for the purpose hereinbefore set forth.

JOSHUA CLAYTON ROBINSON.
